DESIGN FOR A COMBINATION BOTTLE, STOPPER, AND STAND

Jean Desprez, Paris, France, assignor to S. A. Parfumerie Millot, Paris, France, a corporation of France

Application September 25, 1935, Serial No. 58,696

Term of patent 14 years

To all whom it may concern:

Be it known that I, Jean Desprez, a citizen of the Republic of France, residing at Paris, France, have invented a new, original, and ornamental Design for a Combination Bottle, Stopper, and Stand, of which the following is a specification, reference being had to the accompanying drawing, forming a part thereof.

In the drawing:—

Fig. 1 is a front view of the combination bottle, cap and base showing my design.

Fig. 2 is a top plan view.

Fig. 3 is an enlarged perspective view of the cap and top of the bottle.

I claim:—

The ornamental design for a combination bottle, stopper, and stand substantially as shown.

JEAN DESPREZ.
